APPARATUS FOR CLOSING WILD WELLS
THROUGH A PRESSURE CHAMBER

John E. Eckel and John S. Hutchison, Tulsa, Okla., assignors to Esso Research and Engineering Company, a corporation of Delaware

Application July 5, 1955, Serial No. 520,025

6 Claims. (Cl. 166—55)

This invention relates to an improved apparatus for controlling a wild petroleum well from which fluids are escaping under pressure. The apparatus is particularly adapted for closing off wild wells that have been drilled in a lake or gulf and on which surface valves, blowout preventers or other surface control devices are not present or are damaged and inoperative.

With any high pressure producing oil well there is always the danger that the well will get out of control and that the well cannot be closed off with the existing equipment. For example when a well is being drilled or repaired the pressure control equipment may become damaged or broken off, so that the pressure of the well can no longer be confined, resulting in a wild well from which gas and oil will rapidly escape and produce a fire hazard, endanger surrounding property and human life, and cause enormous waste of a valuable natural resource. Wells that have blown out as a result of casing failure caused by excessive corrosion present a serious problem since in such cases there will usually be nothing left but the bare casing and therefore no structure such as flanges will be available to use as an anchoring means in attempting to cap the well. Wild wells of this nature present a particularly serious problem in marine installations since corrosion is particularly bad at the water line and the casing may have failed at the water level.

It is an object of the present invention to provide an apparatus for closing off a wild well by cutting through the strings of casing below the top of the well and inserting means for sealing the producing string of casing.

In accordance with the present invention a pressure chamber is fastened and sealed to the outermost casing of the well. Openings are cut through each of the concentric casings, with the exception of the innermost casing, from within the pressure chamber, the pressure chamber is extended through the openings into sealing contact with the outer wall of the innermost casing, an opening is then cut into the innermost casing from within the extended pressure chamber and sealing means are inserted into the innermost casing to stop the fluid flow.

The nature of the invention and its objects will be more fully understood when reference is made to the accompanying drawings in which:

Figure 1 is an elevational view in section showing the concentric casing strings with the pressure chamber or saddle, valve and drill tool attached, showing the manner in which openings are cut through the outer casings to the innermost casing;

Figure 2 is a transverse sectional view taken on line II—II of Figure 1 showing the packer sleeve set in place against the inner casing;

Figure 3 is a transverse view similar to Figure 2 showing the manner in which an opening is cut into the innermost casing;

Figure 4 is a transverse sectional view showing the inner casing seal set in place;

2

Figure 5 is a perspective view of the expandable seal before expansion;

Figure 6 is a similar view of the seal after expansion; and

5 Figures 7 and 8 are perspective views of the reinforcing leaf springs before and after expansion, respectively. In practicing this invention the first step is to attach a pressure saddle to the outermost string of casing to provide a pressure chamber through which the subsequent 10 operations can be undertaken.

Referring to Figure 1, a portion of a well is shown in sectional elevation, the well having three concentric strings of casing 10, 11 and 12 which extend out of a lake bed 13 to a region somewhere above the level 23 of the lake. In the first stage of the procedure for closing off the wild well a saddle 14 is taken beneath the lake surface by divers and welded or bolted and sealed in place on the outer casing 10. In the embodiment shown the two halves of the saddle are fastened together by bolts 15. A ring seal 16 prevents leakage into the saddle opening. A valve 17 is then attached to the saddle by means of the flanges shown in the figures. A lubricator drill tool 18 is then attached to the outer flange of the valve, the valve 17 is opened, a drill and reamer bit 20 is extended by the drill tool 18 through the valve into the pressure chamber provided by the saddle, and holes 21 and 22 are cut through the two outer casings 10 and 11. The drill is then retracted into the drill tool, the valve 17 is closed and the drill tool is removed from the valve.

20 The drill tool 18 is commercially available and is of the nature shown on page 1918 or page 3436 of the 1954—55 edition of the Composite Catalog of Oil Field and Pipeline Equipment (Gulf Publishing Company).

25 The drill and reamer bit is removed from the drill tool 18 and a setting stem 28 shown in Figure 2 is attached to the drill tool. A packer sleeve 24 is fixed to the outer end of the setting stem and the tool 18 is again attached to the valve 17, the valve is opened and the drill tool is used to push the sleeve 24 through the pressure chamber 30 and the openings 21 and 22 so that the seals 25 on the leading edge of the packing sleeve will be forced into sealing engagement with the outside of the innermost string of casing 12. Sealing engagement between the packing sleeve and the innermost string of casing may also be obtained by resistance welding, provided the setting tool used for inserting the packing sleeve is properly equipped to perform such contact welding.

35 The packing sleeve is provided with annular seals 30 to seal the annulus between the wall of the packing sleeve and the pressure saddle 16. Retainer slips 26 on the exterior of the sleeve lock the sleeve in place. After the sleeve has been locked in position, the setting stem 28 is released by moving the projection 29 on the stem out of engagement with the J-slot 27 in the wall of the packing sleeve. The setting stem is then retracted into the drill tool and valve 17 is closed.

40 An intermediate step of operation may also be used. In this step the packing sleeve is not seated against the innermost casing until sufficient cement has been pumped through it to fill the annular space between casing strings 11 and 12.

45 After valve 17 has been closed, the drill tool 18 is removed from the valve and the setting stem 28 is replaced by a drill and reamer 31 of sufficiently small diameter to pass through the packing sleeve 24 as shown in Figure 3. The drill tool 18 is again attached to the valve 17, the valve is opened and the drill tool extends the drill and reamer through the sleeve 24 to cut an opening 32 into the innermost casing 12. The drill and reamer are then retracted into the drill tool, the valve 17 is closed and the drill tool is removed from the valve.

An expandible sealing device is then attached to the drill tool, the drill tool is again attached to the valve, the valve is opened and the expandible seal is thrust through the packing sleeve into the bore of the inner casing 12. The seal is so designed that when it strikes the opposite interior wall of the casing it expands and seals the bore of the casing.

The details of the expandible seal are shown in Figures 4 to 8 inclusive. The sealing device includes a cylindrical case 34 which slidably receives a plunger 37. Supported at the outer end of the cylindrical case within the slot are a pair of leaf springs 39 which are molded into a body of expandible material 38 such as rubber or the like. The leaf springs are pivotally fastened to each other at each end with the pins 36. The case 34 is inserted through the sleeve 24 until the rounded nose portion 40 engages the far wall of the innermost casing 12. Then, when the plunger 37 is thrust through the cylindrical case by the plunger, the leaf springs are bowed outwardly and the expandible material 38 is likewise forced outwardly so that the entire circular cross section of the casing bore is sealed off. For simplicity of illustration the nose 40 has been omitted from Figures 5 and 6.

The cylindrical case is provided at its outer end with an inner annular groove 42 into which latches 43 on the plunger are forced when the plunger has been forced through the casing. Thus the expanded seal is locked into place after the desired sealing has been effected. The cylindrical case 34 is also provided with locking slips 45 that engage the inner wall of the packing sleeve 24 and thus prevent outward movement of the cylindrical casing once it has been set in place. After the expandible seal has been forced into its sealing position, the setting stem is released from the pressure tool by means of the release device 46, the pressure tool is retracted through the valve, the valve is closed and the pressure tool is removed from the valve, leaving the well closed in.

It is to be understood that this invention is not to be limited to the specific disclosures presented herewith and that modifications thereof are possible and are contemplated which will not depart from the spirit and scope of the invention as defined in the following claims.

What is claimed is:

1. An assembly for closing off fluid flow through the innermost of a plurality of concentric strings of casing which comprises a sleeve member extending through

aligned openings in the walls of said casing strings into sealing engagement with the periphery of an opening in the wall of the innermost of said casings, a cylindrical case fitting within said sleeve and extending within said innermost casing, expandible sealing means supported on the inner end of said case and means for expanding said sealing means within said innermost casing.

2. Assembly as defined by claim 1 wherein said expanding means comprises a cylindrical plunger fitting slidably within said cylindrical case whereby to force said sealing means out of said case on motion of said plunger through said case.

3. Assembly as defined by claim 1 including leaf spring supports within said sealing means to impart rigidity thereto.

4. In an assembly for closing off fluid flow through the producing string of a plurality of concentric casing strings in a well including a pressure chamber attachable to the outermost casing string, cutting means operative from within said pressure chamber to cut holes through each of said casing strings and valve means attached to said pressure chamber to provide access to said holes, the improvement which comprises a sleeve extending from said pressure chamber through the holes in said casing strings and into the producing string, means to seal said sleeve annularly relative to each casing string, an expandible sealing means insertable through said pressure chamber and said sleeve into said producing string, and interengaging means between said sealing means and said sleeve to lock said sealing means in position.

5. An apparatus as defined in claim 4 in which the expandible sealing means comprises a cylindrical case, a body of expandible material at one end of said case, leaf spring members molded within said expandible material and pivotally supported at each end to said cylindrical case, and a plunger movable within said case to thrust against said expandible material.

6. An apparatus as defined in claim 5 in which the expandible material is rubber.
